UNITED STATES PATENT OFFICE

CHARLES I. RICHART, OF WHITTIER, CALIFORNIA

SCREW HOLDING DEVICE

Application filed September 18, 1930. Serial No. 482,698.

This invention is a device for holding a screw in place while starting its threaded engagement, and provides for holding the screw in operative position without steady-ing it by the fingers, thereby particularly adapting the device for use in driving screws at points more or less difficult of access.

It is an object of the invention to provide a holding means which may be supported and operated from a point remote from the screw, and which may be held in the hand with its actuating mechanism conveniently accessible to the fingers.

It is a further object of the invention to adapt the holding device for mounting on the shank of a screw driver so that a screw may be securely held in place relative to the blade of the screw driver with the blade engaging the slotted head of the screw, and the holding means readily operable by the fingers of the hand which grips the screw driver, so that after the threaded engagement has been started the holding means may be readily released and withdrawn and thus permit the screw being driven home in usual manner.

It is a still further object of the invention to provide a holding means of extremely simplified construction and operation, but adapted to positively and securely hold a screw and readily operated by a simple mechanism actuated by the fingers.

Further objects of the invention will be readily understood from the following description of the accompanying drawings, in which:

Fig. 1 is a front elevation of the holding device in operative position.

Fig. 2 is a similar view showing the holding device disengaged from a screw after its threaded engagement has been started.

Fig. 3 is a side elevation of the device in retracted, inoperative position.

Figs. 4, 5 and 6 are detail sections on the lines 4-4, 5-5 and 6-6 respectively of Fig. 3.

The holding device is an elongated structure of restricted cross-sectional area having a gripping means at one end and actuating means at its opposite end so that the grip-

ping means may be inserted and then operated in a space which is difficult of access, and in practice the holding device is preferably mounted on the shank of a suitable tool so that it is supported by the hand which 55 grips the handle of the tool, with the fingers of said hand convenient to the actuating mechanism of the holding device, and the gripping means of the holding device adjacent the working end of the shank of the tool. 60

The holding device is adapted to support a screw, bolt or other fastening or connecting means which must be steadied in position until its operative engagement with the work has been started, and the tool upon the 65 shank of which the holding device is preferably mounted may be a screw driver, wrench or the like adapted to engage and drive home the object which is supported by the holding device. The illustrated embodiment of the invention shows a holding device adapted to support a screw or other threaded element having a slotted head, with the holding device mounted upon the shank 70 of a screw driver which has a usual blade for 75 engaging the slot in the head of the screw; and the invention will therefore be herein-after described and claimed with reference to a "screw" and a "screw driver", it being understood however that such terms are to be 80 interpreted in their broad sense of any element which is adapted to be first supported in operative position and then driven home by a suitable tool engaging the head of the element. 85

Referring to the drawings, cooperating, normally expanded spring jaws 1 are adapted for contraction by an annulus 2 which is slidable longitudinally on the shanks 3 of the jaws, and the annulus 2 may be longitudinally shifted by a strip 4 projecting rearwardly therefrom and terminating in a finger hold 6. The shanks 3 of the jaws are preferably supported by a rearwardly projecting strip 7 which preferably terminates in a finger hold 8, and the strip 4 may be slidably guided relative to strip 7 by extending the strip 4 through a keeper 9 on strip 7 and thence rearwardly through a guide opening 10 in the finger hold 8, so that the finger 100

hold 6 at the rear end of strip 4 is spaced rearwardly from finger hold 8.

It will thus be seen that with annulus 2 retracted on shanks 3, the jaws 1 may be slipped over the head of a screw A, and by operating the finger hold 6 the annulus 2 may then be projected forwardly relative to the shanks of the jaws so as to contract the jaws and thus grip and support the screw as shown 10 in Fig. 1. By supporting the holding device at some point spaced rearwardly from its jaws, the screw A may thus be inserted in a space which is difficult of access, ready for starting the threaded engagement of the 15 screw.

The holding device is preferably supported on the shank 12 of a screw driver B so that with the screw A held in operative position ready for its threaded engagement, the screw 20 driver may drive the screw home; and for this purpose the shank of the screw driver preferably has a flat side adapted for flat sliding abutment of strips 4 and 7, with keepers 13 which project from strip 7 slidably embracing the shank of the screw driver, and the sliding movement of strip 7 limited by abutments 14 on the shank 12 adapted for engagement by one of the keepers 13. A keeper 15 at the rear end of strip 4 preferably also 30 embraces shank 12, and tends to engage the finger hold 6, which is of resilient material, with a notch 16 in the shank 12 so as to releasably hold the strip 4 in inoperative position with annulus 2 retracted for normal expansion of jaws 1.

In practice the jaws 1, shanks 3 and supporting strip 7, together with keepers 9 and 13 and finger hold 8, are preferably stamped from a single piece of metal, with finger hold 40 8 bent at right angles to strip 7, and the keepers 9 and 13 comprising oppositely projecting ears which are bent toward one another to form closed annuli as shown in Figs. 5 and 6, and the shanks 3 and the jaws 1 projecting forwardly from the ears which form one of the keepers 13 as shown in Fig. 3. In similar manner the strip 4 together with finger hold 6 and annulus 2 may be a single stamping, with finger hold 6 while it still forms a prolongation of strip 4 projected through guide opening 10 and then bent as shown in Fig. 3, and the annulus 2 comprising oppositely projecting ears which are bent toward one another so as to embrace shanks 3 as shown in Fig. 4. 50 The keeper 15 may be a separate stamping suitably fixed to strip 4 after assembly of the parts.

As shown at Fig. 3, the screw holding device is in inoperative position permitting ordinary use of the screw driver, the strip 4 being retracted for normal expansion of jaws 1 and held in such retracted position by the spring-projected finger hold 6 releasably engaging the notch 16, and the strip 7 being 60 also retracted so that jaws 1 are spaced rear-

wardly from the blade 17 of the screw driver, with the strip 7 preferably held in such retracted position by the spring jaws 1 releasably engaging notches 18 which may be formed in the shank of the screw driver at its junction with blade 17.

When the holding device is to be used, the thumb of the hand which grips the handle of the screw driver is pressed against finger hold 8 so as to project jaws 1 as shown in Fig. 2, and the head of screw A is then engaged by the blade of the screw driver with the jaws 1 fitting under the head of the screw, whereupon the strip 4 is projected forwardly by pressure of the thumb against finger hold 6, thereby contracting jaws 1 and firmly gripping the screw as shown in Fig. 1. The screw is thus readily operatively positioned and its threaded engagement is started by turning the screw driver and as soon as the threaded engagement is sufficient to hold the screw in place, annulus 2 is retracted by reverse pressure of the thumb against finger hold 6, thereby releasing jaws 1 as shown in Fig. 2 so that they may be disengaged from the screw. By reverse pressure of the thumb against finger hold 8 the jaws are then retracted as shown in Fig. 3, so that the screw may be driven home in usual manner with the holding device out of the way.

The invention thus provides extremely simple and readily operated means for holding a screw in place until its threaded engagement is started, with the holding device then adapted for ready disengagement and retraction so that the screw may be driven home in usual manner.

I claim:

1. A screw holding device comprising a longitudinal strip having a finger hold at its rear end and laterally projecting ears adjacent its forward end with shanks projecting forwardly from the ears and terminating in spring jaws, the ears being adapted to be bent around the shank of a screw driver for sliding movement longitudinally thereof with the longitudinal strip projecting rearwardly along the shank of the screw driver and the shanks of the spring jaws projecting forwardly along opposite sides of the blade 105 of the screw driver so that the spring jaws are adapted for longitudinal projection or retraction relative to said blade, the shanks of the spring jaws being bent so as to normally laterally expand the jaws, and a second longitudinal strip having a finger hold at its 110 rear end and laterally projecting ears at its forward end, the last mentioned ears being adapted to be bent around the operatively positioned shanks of the spring jaws for sliding movement longitudinally thereof with the second mentioned strip projecting rearwardly along the shank of the screw driver and said operatively positioned second mentioned ears adapted to contract the spring 115 120 125 130

- jaws by forward shifting of said ears along the normally bent shanks of the jaws.
2. A screw holding device comprising a strip having laterally projecting ears with shanks projecting forwardly from the ears and terminating in spring jaws, the ears being adapted to be bent around the shank of a screw driver for sliding movement longitudinally thereof with the shanks of the
- 10 spring jaws projecting forwardly along opposite sides of the blade of the screw driver so that the spring jaws are adapted for longitudinal projection or retraction relative to said blade, the shanks of the
- 15 spring jaws being bent so as to normally laterally expand the jaws, and a second strip having laterally projecting ears adapted to be bent around the operatively positioned shanks of the
- 20 spring jaws for sliding movement longitudinally thereof so as to contract the spring jaws by forward shifting of the ears of the second strip along the normally bent shanks of the jaws.
3. A screw holding device comprising a strip having laterally projecting ears with shanks projecting forwardly from the ears and terminating in spring jaws, the ears being adapted to be bent around the shank of a screw driver for sliding movement longitudinally thereof with the shanks of the
- 25 spring jaws projecting forwardly along opposite sides of the blade of the screw driver so that the spring jaws are adapted for longitudinal projection or retraction relative to
- 30 said blade, the shanks of the spring jaws being bent so as to normally laterally expand the jaws, and means encircling the shanks of the
- 35 spring jaws for sliding movement longitudinally thereof so as to contract the spring jaws by forward shifting of said encircling means along the normally bent shanks of the jaws.
4. A screw holding device comprising spring jaws projecting forwardly along opposite sides of the blade of a screw driver and adapted for longitudinal projection or retraction relative to said blade, the shank of the spring jaws being bent so as to normally laterally expand the jaws, and a strip
- 45 having laterally projecting ears adapted to be bent around the shanks of the spring jaws for sliding movement longitudinally thereof so as to contract the spring jaws by forward shifting of said ears along the normal-
- 50 ly bent shanks of the jaws.
5. A screw holding device comprising a longitudinal strip having a finger hold at its rear end and laterally projecting ears adjacent its forward end with shanks projecting
- 55 forwardly from the ears and terminating in spring jaws, the ears being adapted to be bent around the shank of a screw driver for sliding movement longitudinally thereof with the longitudinal strip projecting forwardly along the shank of the screw driver
- and the shanks of the spring jaws projecting forwardly along opposite sides of the blade of the screw driver so that the spring jaws are adapted for longitudinal projection or retraction relative to said blade, the shanks of the
- 70 spring jaws being bent so as to normally laterally expand the jaws, and means encircling the shanks of the spring jaws for sliding movement longitudinally thereof so as to contract the spring jaws by forward shifting of said encircling means along the normally bent shanks of the jaws.
6. A screw holding device comprising spring jaws projecting forwardly along opposite sides of the blade of a screw driver and adapted for longitudinal projection or retraction relative to said blade, the shanks of the
- 75 spring jaws being bent so as to normally expand the jaws, and a longitudinal strip having a finger hold at its rear ends and laterally projecting ears at its forward end, said ears being adapted to be bent around the shanks of the spring jaws for sliding movement longitudinally thereof with the longitudinal strip projecting rearwardly along the shank of the screw driver and said operatively positioned ears adapted to contract the spring jaws by forward shifting of said ears along the normally bent shanks of the jaws.
